UNITED STATES PATENT OFFICE.

CHARLES R. WENNERSTROM, OF NEW YORK, N. Y.

EXTENSION-TABLE.

1,342,481.

Specification of Letters Patent.

Patented June 8, 1920.

Application filed December 4, 1919. Serial No. 342,812.

To all whom it may concern:

Be it known that I, CHARLES R. WENNERSTROM, a citizen of the United States, and resident of the city of New York, in the 5 county of Bronx and State of New York, have invented a certain new and useful Extension-Table, of which the following is a specification.

This invention relates to extension tables, 10 and particularly to that type wherein the extension leaves are carried directly by the table, and which is distinguished from those in connection with which loose leaves are provided and set wholly manually into 15 place upon separation of the table-top sections, the former type of tables being usually adapted to set in the leaves automatically or semi-automatically upon the separation of the table-top sections. The loose- 20 leaf tables are usually round when in folded state and are extended to an oval-like elongated configuration, while the tables of the said automatic type are so contrived that they have to be built in square or rectangular 25 shapes, and as round shaped tables are much more advantageous than the rectangular tables, the latter are deemed objectionable, as evidenced by the almost universal use in dining-rooms of round extension 30 tables at the present time.

The principal object of my invention is to provide a simple, inexpensive, economically and conveniently manufacturable, conveniently utilizable, strong, durable, reliable, efficient, and improved extension table 35 of the above mentioned type.

Another object is to provide an extension table of the said type, which will be round when in the folded or contracted position, 40 but which when extended will assume an elongated form exactly similar to that of the extended tables which utilize loose leaves in their operation.

Other objects and advantages will herein- 45 after appear.

In the accompanying drawings,—

Figure 1 shows a general sectional elevation of the extension-table.

Fig. 2 is a bottom plan view of the table 50 shown in Fig. 1.

Fig. 3 shows a detail of the extension-table.

To the post 1, mounted upon a base 2, is secured an extension-leaf 3, on top of which 55 normally rests a pair of usual semi-circular table-top sections 4, 5, when the table is in

folded condition. For convenience of illustration the post 1 is shown broken away and connected with the leaf 3 by the dash and dot lines 1^a. Rails 7 are secured to the 60 underside of the leaf 3 and extend beyond its sides 8, and filler boards 9, 10 secured to the undersides of the sections 4, 5, respectively rest upon said rails when the sections are located on top of the leaf 3 in the 65 folded condition of the table, whereby the rails 7 and boards 9, 10 serve to provide firm support for the table-sections 4, 5 beyond the leaf 3 when the latter are in their folded condition, in which state they rest but 70 partially on top of the leaf 3, as indicated by the section 4 in Fig. 1. To the underside of the board 9 is secured a pair of guide-rails 11 which extend therefrom underneath the leaf 3 and are located against the support-rails 7 adjacent their inner sides 12 that face each other, and similar guide-rails 13 secured to the board 10 are located against the rails 7 adjacent their opposite sides 14. Normally or when the table is in 75 80 folded condition its sections 4, 5 are located on top of the leaf 3 with their edges 15 adjacent each other and thereby constitute a regular round-shaped table, as shown in Fig. 2. When it is desired to extend the 85 table, the sections 4, 5 are drawn away from each other and slid along the leaf 3 until the edges 15 of the sections pass by the edges 8 of the leaf, whereupon the sections drop down upon the support rails 7 and rest 90 thereon on a level with the leaf 3, as indicated by the position of the section 5 in Fig. 1. As the top-sections 4, 5 drop down to the level of the leaf 3 and the guide-rails 11, 13 come down therewith, pins 16 located at the 95 extremities of said rails and forming part thereof enter into yokes 17 of hooks 18 secured to the under side of leaf 3, and in this manner these pins lock the top-sections against further extension and also maintain 100 said sections in firm state against any swinging or downward dislocation of their ends 19. In order to again fold the table it requires merely a slight lifting of the end 19 of each top-section, to bring its under surface on a level with the top of leaf 3, and then sliding the section along said leaf until it reaches the center thereof, the pins 16 leaving the yokes 17 and thereby readily unlocking from the hooks 18 at the very commencement of the sliding of the top-sections 105 toward each other.

The length of the leaf 3 is less than the extent of the diameter of the table, in order that the leaf may be completely encompassed by the side-rail 6 of the table-top, 5 and hence when the table is extended a gap is left at each end of the leaf bounded by the edge 20 thereof and the edges 15 of the top-sections. To each edge 20 of leaf 3 is hinged a board 21 which is normally maintained underneath the leaf by a spring 22 10 Fig. 3, but which may be swung, contrary to the tension of said spring, to the position shown by the dash and dot lines, at a level with the leaf, in which position it may be securely locked by swinging a latch 23, 15 pivoted to the leaf, to a position rightangularly to the board 21, as shown by the dash and dot lines. When the table is extended, therefore, the board 21 is swung to the position shown by the dot and dash lines and the said gap is completely closed up, so that the end of the leaf 3 assumes a form which renders it tangent to the semicircular table sections, and the entire extended table acquires a form similar to that of the extended 20 tables using common loose leaves. Before folding the table the latches 23 are swung back to the position shown and the springs 22 thereupon swing the boards 21 to the inoperative position shown, underneath the leaf 3, after which the table sections 4, 5 may be brought together to fold up the 25 table.

It will be evident that the table top is 30 at all times firm against any downward dislocation, since in the folded condition the sections 4, 5 rest upon the leaf 3 and through the boards 9, 10, upon the rails 7, and the guide rails 11, 13 prevent any downward dislocation of the table ends 19; while when 35 said sections are in extended position they rest firmly directly upon the rails 7 and the rails 11, 13 coöperate with the hooks 18 to prevent downward dislocation of said table ends; the post 1, leaf 3, and rails 7 being 40 permanently firmly secured together.

Variations may be resorted to within the scope of the invention, and portions of the improvements may be used without others.

Having thus described my invention, I 50 claim:

1. An extension table having the combination of supporting means, an extension leaf fixed to said means, a pair of sections 55 normally resting upon said leaf adjacent each other and constituting the table-top, and means to move said sections apart in the direction of their own planes and drop them to the level of said leaf for extending 60 the table.

2. An extension table having the combination of supporting means, an extension leaf fixed to said means, a pair of sections 65 normally resting upon said leaf adjacent each other and constituting the table-top,

and means to move said sections apart in the direction of their own planes and drop them to the level of said leaf and at either side of the leaf for extending the table.

3. An extending table having the combination of supporting means, an extension leaf fixed to said means, a pair of sections normally resting upon said leaf adjacent each other and constituting the table-top, means to move said sections apart in the direction of their own planes and drop them to the level of said leaf for extending the table, and means to extend said leaf in a direction transversely to the direction of movement of said sections. 70 75 80

4. An extension table having the combination of supporting means, an extension leaf fixed to said means, a pair of sections normally resting upon said leaf adjacent each other and constituting the table-top, means to move said sections apart in the direction of their own planes and drop them to the level of said leaf for extending the table, and means to extend said leaf longitudinally. 85 90

5. An extension table having the combination of supporting means, an extension leaf fixed to said means, a pair of circular sections constituting the table-top normally resting upon said leaf adjacent each other 95 and completely covering said leaf, means to move said sections apart in the direction of their own planes and drop them to the level of said leaf for extending the table, and means to extend said leaf in a direction transversely to the direction of movement 100 of said sections to fill the gap created by the rotundity of said sections.

6. An extension table having the combination of supporting means, an extension leaf fixed to said means, a pair of sections normally resting upon said leaf adjacent each other and constituting the table-top, means to move said sections apart in the direction of their own planes and drop them 105 to the level of said leaf for extending the table, and means to extend said leaf longitudinally at both its ends. 110

7. An extension table having the combination of an extension leaf, a pair of circular sections constituting the table-top normally resting upon said leaf adjacent each other and completely covering said leaf, means to move said sections apart in the direction of their own planes and drop them to 115 the level of said leaf for extending the table, and means to extend said leaf in a direction transversely to the direction of movement of said sections to fill the gap created by the rotundity of said sections. 120 125

8. An extension table having the combination of an extension leaf, a pair of curved sections constituting the table-top normally resting upon said leaf and completely covering said leaf, means to render said sections 130

and leaf level with each other for extending the table, and means to extend the ends of said leaf to fill the gap thereat created upon extension of the table.

5 9. An extension table having the combination of an extension leaf, a curved section constituting the table-top normally resting upon said leaf and covering the leaf, means to render said section and leaf 10 level with each other for extending the table, and means to extend the end of said leaf to fill the gap thereat created upon extension of the table.

10. An extension table having the combination 15 of an extension leaf, a curved section constituting the table-top, means to render said section and leaf level with each other for extending the table, and means to extend the end of said leaf to fill the 20 gap thereat created upon extension of the table.

11. An extension table having the combination 25 of supporting means, an extension leaf fixed to said means, a pair of sections normally resting upon said leaf adjacent each other and constituting the table-top, means to draw said sections apart and drop them to the level of said leaf for extending 30 the table, and means to limit the extension movement of said sections and lock them

in extended state and also to maintain said sections against downward dislocation when in extended state.

12. An extension table having the combination of supporting means, an extension 35 leaf fixed to said means, a pair of sections normally resting upon said leaf adjacent each other and constituting the table-top, means to draw said sections apart and drop them to the level of said leaf for extending 40 the table, means to support said sections when resting upon said leaf and when on a level with said leaf, and means to limit the extension movement of said sections and lock them in extended state and also to 45 maintain said sections against downward dislocation when in extended state.

13. An extension table having the combination of an extension leaf, a pair of curved sections constituting the table-top completely covering said leaf, means to render 50 said sections and leaf level with each other for extending the table, and means to extend the ends of said leaf to fill the gap thereat created upon extension of the table. 55

Signed at the city of New York, in the county of New York, and State of New York, this 29th day of November, A. D. 1919.

CHARLES R. WENNERSTROM.
